CLAIM

The ornamental design for a seedling tray, as shown and described.

DESCRIPTION

FIG. 1 is a top, front, right side perspective view of a seedling tray embodying our design with the shading representing an irregular surface;

FIG. 2 is a top plan view thereof;

FIG. 3 is a bottom plan view thereof;

FIG. 4 is a left side elevational view thereof, the right side elevational view being a mirror image thereof;

FIG. 5 is a rear elevational view thereof, the front elevational view being a mirror image thereof;

FIG. 6 is a left side elevation view of a single cell thereof, taken from section 6—6 of FIG. 2, shown at an enlarged scale;

FIG. 7 is a top plan view of the single cell shown in FIG. 6; and,

FIG. 8 is a bottom plan view of the single cell shown in FIG. 6.
